UNITED STATES PATENT OFFICE.

ALFRED B. HOUTZ, OF ELIZABETH CITY, NORTH CAROLINA.

BARREL.

Application filed February 24, 1927. Serial No. 170,583.

This invention relates to certain improvements in barrels and the nature and objects thereof will be readily recognized from the following description of the accompanying drawings illustrating what I now believe to be the preferred embodiment or mechanical expression of my invention from among various other forms, arrangements, combinations and constructions of which the invention is capable within the spirit and scope thereof.

With barrels employed and used particularly for the packing and shipping of vegetables, fruits and such like perishable goods, it is customary in general practice not to close the barrels with a wooden head or closure, but to employ a cloth or textile covering, such as burlap, for the open end of the barrel. These barrels are formed with the usual series of outside hoops, one of which is mounted on and around the outside of the barrel adjacent the open upper end thereof, and it is found in practice that when a barrel of this general type is left exposed to the sun and elements the staves have a tendency to warp or shrink so that they become loose and if a stave shrinks sufficiently to fall from place the barrel will collapse. A further difficulty experienced with this type of barrel, is that, in applying a burlap or the like cover over the end of the barrel, usually a wooden hoop is used to secure the burlap cover in place, this hoop being fitted around the exterior of the barrel over the skirt of the burlap cover and confining such cover in place. The cover confining hoop is attached in position by nailing or stapling the same to the barrel, and great difficulty is encountered because of the tendency of the staves at the upper end of the barrel to fall or collapse inwardly upon the application of blows and pressures on the exterior or outer sides thereof, as will be clear to those familiar with this type of barrel.

It is an object of the present invention to eliminate the possibility of open end barrels collapsing, and to permit of their being exposed for any length of time under any and all conditions without collapse of the barrel due to stave shrinkage or warping.

It is a further object of the invention to eliminate the possibility of collapse of an open end barrel in nailing or securing the cover retaining hoop thereon, as well as to

render such nailing operation easier and more efficient by eliminating inward give or displacement of the staves.

A further object of the invention is to provide a construction of open end barrel such that the staves are internally reinforced against inward collapse by the provision of an interior reinforcing and holding means or member at the open upper end of the barrel.

A further object of the invention is to provide a design and construction of open end barrel in which a ring is inserted in a groove formed on and around the interior of the barrel at the open upper end thereof and is retained by said groove in annular form against buckling or distortion to hold the staves against inward displacement and resulting collapse of the barrel.

With the foregoing and certain other objects and results in view the invention consists in certain novel features and construction and arrangements and combinations of elements as will be more fully and particularly referred to and described hereinafter.

Referring to the accompanying drawings, Fig. 1 is a detailed perspective view of the open upper end of a barrel embodying and including the features of the invention.

Fig. 2 is a detailed vertical section to a portion of the open upper end of the barrel showing a construction and arrangement of inner reinforcing ring or hoop.

A form of barrel is disclosed in the accompanying drawings of the open upper end type in which the problems overcome by the invention are present. The form of barrel shown is purely by way of example and not of limitation and serves to illustrate and bring forth the principles and features of the invention. Obviously, the invention is not limited or restricted to the exact form or construction of barrel here shown.

In the accompanying drawings a barrel B is shown embodying the series of barrel staves S held and retained in barrel forming position and relation by the usual series of exterior wire hoops, one of which, H, as is usual being mounted on and around the outside of the barrel adjacent and in proximity to the open upper end thereof. The exterior hoop H is nailed, stapled or otherwise suitably secured to the barrel, as for example by the usual staples G, as will be clear by reference to the drawings. Now, as explained with a barrel of this type constructed as de-

scribed, upon exposure to the sun and other elements and conditions, the staves S will shrink and warp and if such shrinkage is sufficient the result is the collapse of the barrel by inward falling or displacement of the staves.

According to the invention I provide and form a groove 10 around the inside of the barrel adjacent the open upper end thereof and this groove 10 is preferably, although not necessarily, in alignment with the outside hoop H, or can be positioned spaced above or below such hoop H. In the groove 10 a retaining and reinforcing member in the form of a ring 11 is inserted and positioned and prevents and eliminates possibility of inward falling or displacement of staves S through shrinkage or warping of these staves. The upper ends of the staves S are thus retained and held between the inner ring 11 and outer hoop H, while as is customary and usual the lower ends of the staves are retained and held in barrel forming position and relation by the usual barrel bottom (not shown) as will be readily understood by those familiar with barrels and their construction. The ring 11 is preferably, of a size and diameter, such that it must be forced into groove 10 and in mounted position is under compression and thus exerts a continuous outward pressure against the inner sides of the upper ends of the staves, although all features of the invention are not restricted to such arrangement. The groove 10 receives and retains the ring 11 in proper position against displacement and in annular form to resist forces applied on the exterior of the barrel tending to buckle or distort the ring, so that the staves are secured and held by the ring against displacement.

With the interior reinforcing member or ring 11 of the invention in mounted position

in a barrel B, when the burlap or other material cover retaining and securing hoop (not shown) is applied around the exterior of the barrel between hoop H and the upper edge of the barrel, it can be quickly, readily nailed or stapled into position because the ring 11 holds the staves backed up and sufficiently rigid for this operation, and further all possibility of displacement of the staves S and collapse of the barrel due to the blows and forces applied to the exterior of the staves is done away with.

Attention is here directed to the fact that while hoops of the endless metal ring type are shown the invention is not so limited, as a split ring or hoop of the expansible type can be used and inserted in groove 11 to exert continuous outer holding pressure on the upper ends of the barrel staves.

It is also evident that various changes, modifications, variations and substitutions might be resorted to without departing from the spirit and scope of my invention, and hence I do not wish to limit myself to the exact and specific disclosures hereof.

What I claim is:

A stave barrel of the open-top type having an exterior hoop surrounding the upper end portions of the staves, and an internal ring within the upper end portion of the barrel to sustain the staves under shrinkage and loosening from collapsing inwardly, said barrel formed with an internal annular groove across the inner sides of the upper end portions of the staves in which said ring is seated and by which it is held in annular stave sustaining form and against buckling or distortion.

Signed at Washington, D. C., this 23rd day of February, 1927.

ALFRED B. HOUTZ.
